US00D838096S

(12) **United States Design Patent** (10) **Patent No.:** **US D838,096 S**
(45) **Date of Patent:** **** Jan. 15, 2019**

(54) **SHOE**

(71) Applicant: **NIKE, Inc.**, Beaverton, OR (US)

(72) Inventor: **Leo S. Chang**, Portland, OR (US)

(73) Assignee: **NIKE, Inc.**, Beaverton, OR (US)

(**) Term: **15 Years**

(21) Appl. No.: **29/654,614**

(22) Filed: **Jun. 26, 2018**

(51) **LOC (11) Cl.** 02-99

(52) **U.S. Cl.**

USPC **D2/972**

(74) *Attorney, Agent, or Firm* — Banner & Witcoff, Ltd.

(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is a top view thereof;

FIG. 5 is a front perspective view of an alternate embodiment of a shoe showing my new design;

FIG. 6 is a side view thereof;

FIG. 7 is a rear perspective view thereof;

FIG. 8 is a top view thereof;

FIG. 9 is a front perspective view of an alternate embodiment of a shoe showing my new design;

FIG. 10 is a side view thereof;

FIG. 11 is a rear perspective view thereof; and,

FIG. 12 is a top view thereof.

The broken lines immediately adjacent to the photographic area define the bounds of the claimed design and form no part thereof. The broken lines depicting the remainder of the shoe show features that form no part of the claimed design.

1 Claim, 12 Drawing Sheets
